UNITED STATES PATENT OFFICE.

WARNER LEWIS, OF STONE BLUFFS, INDIANA.

TIRE-HEATING FURNACE.

SPECIFICATION forming part of Letters Patent No. 278,153, dated May 22, 1883.

Application filed February 16, 1883. (No model.)

To all whom it may concern:

Be it known that I, WARNER LEWIS, of Stone Bluffs, in the county of Fountain and State of Indiana, have invented a new and Improved Tire-Heater, of which the following is a full, clear, and exact description.

My invention consists of an annular furnace with a dome having draft-regulating deflectors for controlling the heat, all as hereinafter fully described.

Reference is to be had to the accompanying drawings, forming part of this specification, in which similar letters of reference indicate corresponding parts in all the figures.

Figure 1 is a sectional elevation of my improved tire-heater. Fig. 2 is a plan of the dome inverted, and Fig. 3 is a plan of the furnace with the dome removed.

I make an annular furnace-chamber, *a*, by building up the brick center *b* and the outer wall, *c*, a suitable height—say about two feet—the center *b* filling as much of the space as is not required to be heated, and the outer wall being suitably large in diameter to inclose an annular space, *a*, of suitable dimensions to receive the largest tires to be heated, and between these two brick walls I fit an annular grate, *d*, on which to make the fire for heating the tires *e*, for the proper support of which above the fire I provide the arms *g*, projecting radially from one or the other or both of the walls.

Over the furnace *a*, I arrange a sheet-iron dome, *h*, with a smoke-pipe, *i*, at the top to carry off the products of combustion, the dome being fixed removably, and I provide a chain, *j*, pulley *k*, and lever *l*, or it may be any equivalent contrivance, for raising the dome when it may be required to open the furnace for the

introduction or removal of the tires to be heated. The smoke-pipe will either pass up through the building, so that it will rise in the hole of the roof through which it projects, or it will have a telescopic joint at any suitable place below the roof for allowing the dome to be raised properly.

At suitable intervals around the base of the wall *c*, I arrange draft-openings *m* for the proper supply of air for combustion, and directly over these I attach deflectors *n* to the dome, which cover the furnace, except at the passages *o*, and thus cause the draft to diverge from the straight course upward and promote more uniform combustion on the grate.

At the top of the dome I arrange a damper, *p*, for regulating the draft as required.

Thus it will be seen that I provide a simple and efficient device naturally adapted to the peculiar form of tires, by which they can be heated much more rapidly and economically, and also better, than in the common open-air fire, and with more comfort and less labor for the operatives.

I am aware that the furnace and movable dome are both old and not of my invention, but

What I do claim is—

The furnace *a b c*, having in its dome *h* and on its center piece, *b*, the deflectors *n*, separated by the openings *o*, and upwardly inclined toward the center, as and for the purpose specified.

WARNER LEWIS.
